UNITED STATES PATENT OFFICE.

TURNEY E. BUCK, OF CHICAGO, ILLINOIS, ASSIGNOR TO WILLIAM O. DUNTLEY, OF CHICAGO, ILLINOIS.

WASTE-STEAM DETECTOR AND RECORDER.

1,243,702.

Specification of Letters Patent. Patented Oct. 23, 1917.

Application filed January 6, 1914. Serial No. 810,565.

To all whom it may concern:

Be it known that I, TURNEY E. BUCK, a citizen of the United States, residing at Chicago, in the county of Cook and State of Illinois, have invented a certain new and useful Waste-Steam Detector and Recorder, of which the following is a specification.

My invention relates to mechanism for detecting the waste of steam from steam boilers, 10 more particularly locomotive boilers, such mechanism being exemplified by Zerbee Patent No. 1,027,368 dated May 21, 1912. The object of my invention is to provide the mechanism or device with means for permanently recording the time of the blowing-off of the steam valve such as the safety valve as well as the time of normal condition of the valve, so that not only may the actual time of the blow-off be registered but also 15 the particular locality or localities along the road, in case of a locomotive, where the steam blew off. Another object of my invention is to provide a simple, efficient and reliable device of the character referred to. 20 In the drawing, Figure 1 is an elevation of my device shown attached to a safety valve and illustrating the door of the casing open; Fig. 2 a sectional plan on the line 2--2 of Fig. 1; Fig. 3 a detail view of a portion 25 of the clock movement and the recording strip mechanism.

Referring to the present embodiment of my invention as herein shown the operating parts are mounted in and for the most part 25 inclosed by a box or casing 1 of suitable size and dimensions and having at one side a closure or door 2 which is provided with suitable means for locking and sealing, such as the hasp 3, staple 4 and any suitable lock 30 (not shown) in order to prevent entrance to the interior of the casing by any unauthorized person. By preference this casing is adapted to be removably secured to the safety valve such as the one shown at 5 and 35 to this end and as herein shown the casing is provided with a bracket 6 which partially encompasses the cylindrical body of the safety valve and is secured thereto by means of the strap 7 and bolts 8.

40 A lever 9 is pivoted to the casing in suitable manner as upon the pin 10, the lever extending into the casing and also extraneous thereof, its outer end being provided with an enlarged or fan-tailed plate portion 45 11 which extends over some of the openings 5^a of the safety valve in position to receive

the impact of the escaping steam and to be thereby moved upwardly. In order to limit both the upward and downward movements of the lever the casing is provided 60 with a lower stop 12 and an upper stop 13 projecting horizontally adjacent the lower and upper edges respectively of the lever.

The registering mechanism may, in the broader aspect of the invention, be of any 65 suitable and desired construction adapted to coöperate with the movements of the pencil to effect a permanent record. In the present instance this mechanism comprises a suitable time movement 15 contained within the 70 casing and including a driven spindle 16 on which is mounted a time wheel 17. Two rolls 18 and 19 are pivotally mounted on a carrier plate 20 which is pivoted to the top of the clock movement by means of the bearing pin or spindle 21 on which the roll 18 rotates. A chart or recording strip 22 is carried on and between these two rolls 18 and 19, the former being the supply or unwinding roll and the other the winding roll. The 75 strip is fed synchronously by means of the clock movement through the medium of the time wheel 17 against which the winding roll 19 and the strip are held in yielding frictional engagement. For this purpose the carrier plate 20 is pivoted as described and is held toward the time wheel by the coiled spring 23.

The record strip is marked or calibrated as shown in Fig. 4, the center longitudinal 90 line representing a dividing line between the indications for the blowing-off condition and the normal condition and the transverse lines representing the time.

Describing the operation of the mechanism 95 and assuming that the lever is in its normal position as shown in Fig. 1 the pencil which is at all times in contact with the chart or strip will mark a line above the longitudinal center line of the strip which in practice is a red line, it being understood that the strip is continually moving. When the steam blows off the outer end of the lever is elevated and the inner end is depressed with the result that the mark of the pencil crosses 100 the red center line and causes a line to be drawn therebelow whose length is dependent upon the length of time of the blowing-off of the steam. Just as soon as the steam stops 105 escaping the lever will drop to normal position by reason of gravity and thereupon occupy its normal position above the red 110

- center line of the strip and the pencil will cause a line to be drawn on the strip above the red line of a length depending upon the length of the duration of normal condition.
- 5 By reason of the time markings on the strip the exact time of the blowing-off of the steam and of the normal or closed condition of the safety valve may be determined and in case the device is used on a locomotive 10 it may be readily determined as to the locality or localities on the road just where the valve opened and closed and consequently whether the blowing-off occurred during stops or on the run or at grades, etc.
- 15 The strip constitutes a permanent record of the efficiency of the fireman and enables the employer to accurately determine such efficiency. The construction and arrangement is such that the record cannot be tampered with even though access may be had to the interior of the casing inasmuch as the aggregate time traced by the pencil must correspond to the time that the locomotive 20 has been in service. The stops 12 and 13 which limit the upward and downward oscillation of the lever 9 provide for the straight line tracing by the pencil either above the center longitudinal line or below, as clearly shown in Fig. 4.
- 25 30 I claim:
1. In a device of the class described, the combination, with an escape valve for relieving excess pressure of steam, of recording mechanism and a vane member located 35 outside the steam passage and operated by impact of steam escaping from the valve and arranged to coöperate with said mechanism to effect a permanent record of the duration of the escape of steam.
  - 40 2. In a device of the class described, the combination, with an escape valve for relieving excess pressure of steam, of recording mechanism and a lever located outside the steam passage, one end of which lever 45 is formed as a vane lying in the path of steam escaping from the valve and is moved thereby and the other end is in coöoperative relationship with said mechanism to effect a permanent record of the duration of escape of steam and of the normal condition 50 of the valve.
  - 55 3. In a device of the class described, the combination, with an escape valve for relieving excess pressure of steam, of recording mechanism including a time movement and a record strip moved thereby, and a lever having at one end a marking device coöoperating with the strip and adapted to trace lines thereon, said lever being formed 60 with a vane located outside the steam passage and arranged to be moved by steam escaping from the valve and to thereby move the marking device with respect to the strip.

4. In a device of the class described, the combination, with an escape valve for relieving excess pressure of steam, of recording mechanism including a time movement having a time wheel, a pivoted carrier plate, two rolls mounted thereon, a record strip carried by such rolls, means for yieldingly holding one of the rolls against the time wheel, and a member located outside the steam passage and operated by the impact of steam escaping from the valve and having a marking device moved with respect to the strip when the steam is escaping.

5. In a device of the class described, the combination, with an escape valve for relieving excess pressure of steam, of recording mechanism including a time movement having a time wheel, a pivoted carrier plate, two rolls mounted thereon, a record strip carried by such rolls, means for yieldingly holding one of the rolls against the time wheel, and a pivoted lever equipped at one end with a yieldingly mounted pencil holder and having its other end formed with a vane arranged in the path of steam escaping from the valve to move a pencil held in said holder transversely of the record strip.

6. In a device of the class described, the combination, with a steam boiler and an escape valve thereof, of a casing having a side opening, a lever pivoted in said opening with one end formed as a vane extraneous of the casing and in the path of escaping steam and with the other end within the casing, stops on opposite sides of the opening to limit the lever movements, and recording mechanism arranged within the casing and coöperating with the inner end of the lever to effect a permanent record of the duration of the escape of steam.

7. In a device of the class described, the combination, with an escape valve for relieving excess pressure of steam, of a casing having a side opening, a lever pivoted in said opening with one end extraneous of the casing and in the path of steam escaping from the valve and with the other end within the casing, such latter end being equipped with a pencil, a time movement including a time wheel arranged in said casing, a spring-pressed pivoted carrier plate in said casing, a supply roll carried by the pivoted end of said carrier plate and a record strip on such roll arranged in coöoperative relation with said pencil, and a winding roll for said strip carried by the swinging end of said carrier plate and yieldingly engaging said time wheel.
